ELECTROLUMINESCENT PLATE AND FONT OF CHARACTERS FORMED THEREON

Herbert F. Dickson, Jr., R.D. 1, Seneca Falls, N.Y.

Filed Mar. 11, 1964, Ser. No. 78,966

Term of patent 14 years

(CL. D64—12)

FIG. 1 is a rear perspective view of an electroluminescent plate showing the base character repeated thereon, in accordance with my new design, the transparent front of the plate being plain, and

FIG. 2 is a face view of the basic character and letters and numerals formed therefrom.

This application is a continuation-in-part of an application filed by me on April 4, 1963 bearing Serial No. D. 74,299 and now abandoned.

I claim:

The ornamental design for an electroluminescent plate and font of characters formed thereon, as shown and described.
